Paul E. Richards, Los Angeles, Calif., assignor to
Audiodyne Corporation, Northridge, Calif., a corporation of California

Filed Oct. 15, 1968, Ser. No. 13,998

Term of patent 14 years

Int. Cl. D14—01; D2—02
U.S. Cl. D26—14

FIGURE 1 is a side elevational view of the hat mounted loudspeaker showing my design therefor;

FIGURE 2 is an end elevational view of the loudspeaker shown in FIGURE 1 as taken in the direction of arrows 2—2 thereof;

FIGURE 3 is a top plan view of the loudspeaker;

FIGURE 4 is a side elevational view of the loudspeaker as taken in the direction of arrow 4—4 of FIGURE 2;

FIGURE 5 is an end view of the loudspeaker taken from the opposite end shown in FIGURE 2; and

FIGURE 6 is a bottom plan view of the loudspeaker.

The showing in broken lines of a hat in FIGURE 1 and a chin strap in FIGURES 2 and 5 is for illustrative purposes.

I claim:

The ornamental design for a hat mounted loudspeaker, substantially as shown and described.
